Elijah Skinner
Letters Patent

The Schedule refers to on these Letters Patent and making part of the same containing a description in the words of the said Elijah Skinner himself of his improvement in the cooking Stove.

To all to whom these presents may come. Be it known that I Elijah Skinner of Sandwich in the County of Strafford and State of New Hampshire have invented a new and useful improvement in the cooking Stove, taken from the oven and fender named in my specification of an improvement in the mantle and fender of fire places in 1822, and from other cooking Stoves and that the following I think is a full and exact description of said improvement as invented by me. First I make a plate of cast iron about two fifths of the width of which is made with triangular corners to correspond with a common fire place and the residue is an oblong square from three to four feet in length and from eighteen inches to two feet in width as may be required according to the size of the stove. At the two front corners are circular projecting places of any required size of the form of three quarters of a circle for funnels as at A, & D, & I and near the back corners are ovaling places for funnels as at B, & I. I also make in said plate the common openings for cooking apparatus. I then make a cast iron plate or frame at C, D, about two or three inches wide and of the same form and compass as the front and ends of the above said plate with round projecting corners at part of the front of which is formed into a door stool as at B. This latter plate is for the stove to rest upon. Then make another cast iron plate for the front of the stove the length of which is calculated to extend as far as to the two projecting corners of the plate just mentioned and from thirteen to fifteen inches or any required width leaving a suitable opening for the doors. I next make two end plates of cast iron of the same width and of different length to extend from the front circular corners to the angles of the top plate which are fitted to the fire place as aforesaid. I then make a sort of funnel of sheet iron for each front corner about three fourths of a circle and equal in length to the width of the front plate.

plate with lip on each side of each forming with an angle plate a corner piece with the front and side plates and the circular part to correspond with the first mentioned place. I then let my front and side plates and circular funnel into a groove prepared in the bottom plate or frame causing the lips of the funnel to rest upon the front and side plates on the inside. I next place on my top plate before described which is connected with the front and side funnels also by grooving. I have also iron rods at the corner passing through the top and bottom plates in such a position as to confine the corner funnels to the casting by the lips of same. And the whole is secured together in common form. I then make and hang in position doors of any required size, with appertures and dampers in common form. I have also appertures and dampers in them to be left in the door when required and in some cases a door on either side. Doors are made for the boiler or they are fitted to the stone as in other cooking stoves. I then place on the corner plates and on the funnels square plates and covering the channelling or passing off in any required direction so that a damper is each near the bottom. On the first mentioned back flue I fit two ovaling funnels from fourteen to eighteen inches in length usually with a damper in each near the bottom. The dampers are all made and fitted to the inside of the funnels with a square rod passing through a socket in the damper and that part which rests upon the funnel is one end and a nail to the other and a nut and screw is fitted where one end and a bow upon the other, that part of the rod next the bow being square. I then place the damper into the funnel and pass the rod through holes in the funnel, and through the socket of the damper, and put the nut on to the opposite end, confining the damper in the required position by a square or mortice in the side of the funnel fitted to receive the square end by which the damper is made fast when required and by a hatch I can change the heat from one end to the other of the stove and throw it backward and forward from the front to the back funnels. I then make an iron as follows to be connected with the stove, first I make an along square box of sheet iron of any required length and width suitable for the stove which is called the outside or the frame of which is covered in part with a plate of sheet iron about the length of the stove plate forming a projection for fastening and having a square sliding opening to

over the oven, and the masonry over a long flue corresponding with
 the back part of the stone plate of oven. There is also a flue off
 the top of the case to let out the smoke with a damper. It then may have over
 of the same figure and smaller than the outside case with a plate connected to
 it on part the same as the case leaving an opening for the hood. One may make
 a flue a door in common form. Others set the oven into the case with
 the projection in front of the oven and shutting snug to the case, and make
 the oven fast to the case by a nut and screw in the back side leaving a space
 all around it excepting the part for the passage of the heat and I have pro-
 vision of iron fitted between the case and oven to throw the heat equally
 into every part. A shelf or grate is used in the oven as in common stove ovens.
 When required I make the whole oven of cast iron, having thus finished
 my stove and oven. I next place my stove into the fire place, the back part
 resting on a projection of mason work, or fitted into a groove with the
 finished front part projecting outward on the hearth as at A. I construct
 the back part required by building up in part of mason work at the ends.
 Then place the oven case & oven under the mantle of the fire place the
 back part resting upon mason work and the front resting upon the top of
 the back flue to which it is fitted with the case so fitted to the mason
 work as to leave a space around the ends and back side for the passage of the
 flame as at C. and screw the case to the jamb or coverings of the fire place
 of which it is made fast and may be rendered moveable, and the oven may
 also be removed from the case by turning the screw which connects it to the
 back of the case. A space is left between the top plate and the bottom of
 the masonry that the boiler may sit in part under the oven and the smoke
 conveniently to let off the steam from the boiler. And in the back part of
 this space a small fire place is constructed between the back flues
 as required as at f. in N. & I. What follows is my improvement and
 not previously known in the above described stove as the particular arrange-
 ment & effect of the flues, funnel, damper & oven and the advantages for
 letting off the steam, also the application of the whole to the common open fire
 place as before described Allegations. In fire places where the oven cannot be
 set into the chimney of sufficient depth, it may be projected wholly upon

had made the time in the iron preparation and in the use a number of them with
the help of other of Mason work & of iron may be placed together & you
become a cutting for the top of the course of Mason work leaving a space
between the iron and the stone for the passage of the water. Complete plate
in one case fitting in one of cast iron & one on both ends of this stone and
when like it for sitting arms and shoulders close and the man as places
for border. And when use this stone without the iron the back foundation
for a full back straight up the water upward into a full back into the
throat of the chimney and in small stones only one back about four inches
wide. Sandwiche it off. May 2nd 1835.
